UNITED STATES PATENT OFFICE.

JOSEPH STAFFA AND RUDOLF STAFFA, OF CHICAGO, ILLINOIS.

HAT CARRIER.

Application filed December 11, 1922. Serial No. 606,107.

To all whom it may concern:

Be it known that we, JOSEPH STAFFA and RUDOLF STAFFA, subjects of the Government of Czechoslovakia, and residents of Chicago, in the county of Cook and State of Illinois, have invented certain new and useful Improvements in Hat Carriers; and we do hereby declare that the following is a full, clear, and exact description thereof, reference being had to the accompanying drawings, and to the characters of reference marked thereon, which form a part of this specification.

This invention relates to a novel carrier for ladies' hats of that kind adapted to be attached to the wall of a wardrobe trunk or other support, and shaped to receive the crown of the hat, and refers more specifically to an improved supporting means for the ball shaped carrier by which it is readily attached to and detached from a support,—as the wall or other part of the trunk body.

The object of the invention is to produce a rigid support for the carrier which is simple and economical to manufacture, which provides a firm connection between the carrier and its support, and which enables the hat carrier to be removed from the support in different directions from a locked position thereon.

The invention consists in the elements and combination of elements shown in the drawings and described in the specification, and is pointed out in the appended claims.

35 In the drawings:

Figure 1 is a side elevation of a hat carrier equipped with a support embodying my invention.

Figure 2 is a section on the line 2—2 of 40 Figure 1.

Figure 3 is a section on the line 3—3 of Figure 2.

Figures 4 and 5 are perspective views of the interlocking attachments connected one 45 to the base of the carrier and the other to the support.

Figure 6 is a fragmentary detail showing a modification.

As shown in the drawings, 10 designates 50 the body of the carrier which is of general spherical formation except at its base where it is flattened for attachment to the support. The body of the carrier usually comprises a mass of fibrous material enclosed by a fabric cover. At the flattened side of the ball like carrier there is provided a flat relatively

thick, disk-like foundation member 11, preferably made of wood or other fibrous material; and the margin 12 of the cover fabric is pulled on over the periphery of the disk 60 11 and is attached thereto by nails 13 which extend through a reinforcing band 14 exterior to said margin and through the margin into the disk.

First referring to the construction shown 65 in Figures 1 to 5, inclusive, 16 designates a sheet spring metal bar which is flat throughout its principal length and is attached to the bottom of the disk, as by the nails 17. The side marginal portions of said bar are 70 turned obliquely downwardly to form parallel spring holding flanges 18 which extend from one end of the bar to near the other end thereof. At the latter end of the bar between said flanges it is slotted to form a 75 tongue that is inclined downwardly and is at its outer terminal curved upwardly to form an upturned latch 19 which extends endwise beyond the body of the bar and is provided at the base of said upturned part 80 with a latch opening 20. The said latch is thus cut, as a tongue, from the bar 16, and extends beyond that end of the bar from which it is formed, the bar being slotted at the sides of the base of the tongue to give 85 ample flexibility to the latch.

To the support 15 is attached, as by means of the nails 21, a sheet spring metal plate 22 which is principally flat throughout its dimensions. Said plate is provided near its 90 side margins and between its ends with upturned elongated springy hooks 23 which are parallel with each other and are formed by cutting the metal of the plate longitudinally and transversely and turning the inner 95 edges upwardly about the uncut portions at oblique angles to the plane of the plate. The extreme side margins of the plate 22 are curved upwardly to form steadyng ribs 24 which lie substantially in the planes of the 100 upturned edges of the elongated hooks 23. The said plate extends beyond the ends of said hooks and is transversely curved. Near said ends the plate is cut and struck upwardly to form lugs 25 which are adapted 105 to be engaged by the slot 20 of the latch 19.

The said bar 16 and plate 22 are adapted to be interlocked to each other by placing the flanges 18 of the bar 16 in line with the spaces between the elongated hooks 23 and 110 endwise moving one of the parts relatively to the other so as to bring said flanges be-

neath the hook. By reason of the fact that the oblique flanges 18 are free at both ends and the elongated hooks 23 are likewise free at both ends, such interlocking engagement 5 may be effected by presenting either end of the flanged bar 16 to the hooks of the plate 22.

The plates are locked from endwise movement, when so transversely interlocked by 10. the flanges 18 and hooks 23, by engagement of one of the lugs 25 of the plate with the slot 20 of the latch 19, depending upon that lug which is adjacent to the latch when the bar and plate are, so interlocked. The bar 15 16 and plate 22 are made of metal of some considerable springiness, and the inclined portion of the latch 19 is normally sprung downwardly from the plane of said bar so that when the bar and plate are being interlocked by relative endwise movement thereof the said upturned end of the locking tongue or latch slides along one of the lugs 25 and raises or springs the tongue upwardly until the slot 20 comes into register therewith, 25 whereupon the slotted latch automatically springs downwardly over the tongue to lock the parts together. It will be observed that this automatic locking operation will take place at either end of the plate 22, regardless 30 of the direction in which the bar 16 and the carrier attached thereto is shifted to engage it with the elongated hooks of the supporting plate 22. The said ribs 24 are made of such height that when the bar and plate 35 are thus locked together, the rounded portions of the ribs engage the under side of the disk 11, and their free edges are engaged with the support so that the carrier attached to said plate is braced from laterally tilting movement. Said ribs 24 also have the effect 40 to force the flanges 18 and the elongated hooks 23 into close binding engagement, with the result of further increasing the firmness of the interlocking engagement of the bar 45 with the plate to prevent the former rolling on the latter and to prevent endwise displacement of the plate and bar.

The said bar and plate may be reversed in respect of their attachment to the disk 11 and support 15. Such a structure is shown 50 in Figure 6 wherein the plate 22' is attached to the under side of the disk and the bar 16' is attached to the support. No change in form of the plate and bar is made in this 55 reversal, and like parts of the structure shown in Figure 6 bear the same reference characters as those shown in Figures 1 to 5, inclusive, with the exception of the primary reference characters before mentioned.

60 We claim:—

1. A hat carrier comprising a body to receive a hat crown and having a flat faced foundation member, and sustaining means to detachably sustain said body on a support, comprising spring sheet metal members, one

fixed on said foundation member and the other adapted to be carried by said support, said sheet metal members facing each other and formed with open ended, slidably engageable, laterally oblique flanges and hooks 70 adapted to be engaged and separated by sliding movement of said members in either direction, one of said members having a spring, endwise extending latch to automatically engage a lock projection on the other member through relative endwise movement of said members.

2. A hat carrier and its sustaining means set forth in claim 1, and characterized by steadyng ribs formed on the margins of 80 one member laterally beyond said interlocking hooks and flanges.

3. A hat carrier comprising a body formed with a foundation disc member adapted to be disposed parallel to and face a support, 85 and body sustaining means comprising open-ended, slidably engageable interlocking members adapted to be interlocked and released by movement of said members in either direction, said members being narrower than the circumference of said disc and extending diametrically across said disc.

4. A hat carrier comprising a body formed with a flat base adapted to be disposed parallel to a support, and spring sheet metal members attachable one to said base and the other to the support and extending diametrically across and concealed by said base, and provided with parallel, longitudinally 100 slidably, laterally interlocking flanges and hooks, adapted to be engaged and separated by relative longitudinal movement of said members in either direction, and including locking means automatically engageable upon relatively sliding movement of said members.

5. A hat carrier comprising a flat base adapted to be disposed parallel to a support, spring sheet metal locking members between said base and said support and extending diametrically across said base, parallel, slidably engaged and laterally interlocking flanges and hooks on said members, and a locking tongue integral with one of said members and extending endwise therebeyond and inclined toward the other member, and adapted to be interlocked with the other member automatically upon sliding movement of said members.

6. The hat carrier and its sustaining means set forth in claim 5, and characterized further in that said hooks and flanges are open at both ends of said members to permit locking and releasing by relative movement of said members in either direction.

7. A detachable support for a hat carrier comprising two sheet metal members adapted for attachment to a carrier and a fixed support, one member having within its margin 130 inwardly oblique, longitudinal hooks and the

other member having flanges to laterally and interlockingly engage with said hooks through longitudinal movement of said members, and one of said members having laterally and outwardly beyond said flanges and hooks steadyng ribs raised beyond the plane of said latter member, to prevent rocking movement of said plates on each other.

8. A hat carrier and detachable support-
10 ing means therefor comprising spring sheet metal members lying substantially in parallel planes, and equipped on adjacent faces with parallel interlocking projections brought together in laterally interlocking relation by
15 relative sliding movement of one member relatively to the other, and adapted to be

engaged and released by movement of said members in either direction, one of said members having a spring locking latch inclined towards the other, and the other 20 member having a locking projection at both ends adapted, through endwise movement of one relatively to the other to be automatically engaged by said latch to lock said members from endwise movement.

In witness whereof we claim the foregoing as our invention, we hereunto append our signatures this 17th day of October, A. D., 1922.
